UNITED STATES PATENT OFFICE.

WALTER F. STIMPSON, OF DETROIT, MICHIGAN, ASSIGNOR, BY MESNE ASSIGNMENTS,
TO ESTELLE H. STIMPSON, OF DETROIT, MICHIGAN.

COMPUTING-SCALE.

1,106,323.

Specification of Letters Patent.

Patented Aug. 4, 1914.

Application filed November 5, 1910. Serial No. 590,868.

To all whom it may concern:

Be it known that I, WALTER F. STIMPSON, a citizen of the United States of America, residing at Detroit, in the county of Wayne 5 and State of Michigan, have invented certain new and useful Improvements in Computing-Scales, of which the following is a specification, reference being had therein to the accompanying drawings.

10 The invention relates to computing scales of the automatic type and consists in the various features of construction as herein-after set forth.

In the drawings,—Figure 1 is a sectional 15 elevation; Fig. 2 is a sectional plan view; Fig. 3 is an elevation similar to Fig. 1 showing a modification; and Fig. 4 is a sectional plan view thereof.

A is a base frame containing platform 20 levers B for supporting a platform C preferably of circular form. At one end of the frame A is a lateral extension D having an upwardly extending frame E mounted thereon with an indicator such as computing 25 chart F of segmental or fan-shaped, form surmounting the same. Arranged upon the frame is an automatic weighing mechanism comprising an index hand G which is mounted upon knife edge pivots H, a pendu- 30 lum weight I secured to the index hand and a flexible tape J engaging the pulley or cam K on the index and forming an actuating means therefor.

The mechanism just described is so connected to the platform C as to indicate the exact weight of articles placed thereon, and by means of the computing chart to also indicate the value of the article as computed from various units of price. It is usual 40 with scales of this type to connect the index and the platform through the medium of a single lever or beam on which the platform is supported. This necessitates check rods for the platform to hold the latter from 45 tipping, which in turn requires a base of considerable height to provide the necessary length for these rods. It is one of the objects of the present invention to diminish the height of the base, and to this end in 50 place of a single lever, compound platform levers are employed providing a suitable support for the platform without the use of check rods. As shown, these platform levers B¹ and B² are connected to each other by the 55 intermediate links L, and the platform is

supported thereon by depending lugs C¹ engaging pivotal bearing loops C² which are supported on the knife edge pivots of the levers. The lever B² is provided with the arm B³ which extends into the portion D of the base and is connected to the automatic 60 weighing mechanism through the medium of an intermediate lever or beam M, which also constitutes a tare beam. This beam M is arranged at a higher elevation than the platform C and is fulcrumed at N upon the upward extension E of the frame. The inner end of the beam M is connected with the tape J for operating the index G and deflecting the pendulum weight I. The opposite end of said beam projects beyond the fulcrum and has connected thereto, a counterpoise O which may be provided with detachable weights. There is also a dash-pot P for checking the oscillation of the beam 70 which is preferably mounted in the frame E below the beam M and at one side of the steelyard rod connection L¹ which couples the arm B³ with the beam M.

With the construction just described, the 80 mechanism intermediate the platform and the tare beam forms a manually operable scale which may be employed for weighing by shifting the poise M¹ of the beam M. This mechanism is adjusted to be in perfect 85 balance independent of its attachment to the automatic weighing mechanism. On the other hand, the automatic weighing mechanism including the index, a pendulum weight and other connections, is also in balance independent of its connection with the manually operable weighing mechanism. This facilitates the construction and the sealing 90 of the scale.

I preferably construct the standard E in 95 the form of a hollow case inclosing the mechanism including the greater portion of the beam M, but the end portion of said beam projects outward through a slot Q, 100 and the counterpoise O is secured thereto outside of the case. This counterpoise is preferably of the construction shown in Fig. 3. O¹ is the ball or permanently attached weight, O² is the shelf beneath the ball supported therefrom a sufficient distance to 105 provide space for the detachable weights and clearance for the oscillations of the beam, said shelf being secured by a bracket O³ to the standard E. O⁴ is a guide pin 110 projecting upward from the center of the

shelf O^2 and engaging a recess O^5 in the ball O^1 . O^6 is a detachable weight which when not in use is supported on a shelf O^2 , being slotted to embrace the pin O^4 . This weight may at any time be removed from the pin and placed on the top of the ball O^1 to increase the weighing capacity of the scale. Thus the pin O^4 in connection with the bracket O^2 and hollow ball O^1 performs the double function of a support for the detachable weight or weights and a guide for checking the oscillations of the counterpoise. The position in which the detachable weight is supported is one very convenient for transferring the weight to and from the ball of the counterpoise.

Where the beam M is housed in the standard E , the tare beam is preferably arranged as shown in front of said standard and is mounted upon the beam M by connections to the opposite ends thereof. As shown the outer end of the beam M has a laterally extending arm M^2 and the inner end a projecting arm M^3 , which latter passes through a slot in the housing E . The tare beam M^4 is attached to these arms M^2 and M^3 and the poise M^1 is slidably secured on this tare beam. Thus the tare beam and poise are in a convenient position for inspection and operation while all of the mechanism is housed within the standard.

The weighing platform is preferably arranged to the right and forward of the lateral projection D of the base and the standard E rising therefrom. This places the poise on the tare beam where it may be most conveniently shifted by the left hand of the operator. At the same time the fulcrum of the lever M is to the left of its point of connection with the platform levers. It is evident that the poise must be shifted to the left to increase the weight and to the right to decrease the weight. This is more convenient for operation than would be the case if the poise were shifted in the opposite direction.

The mounting of the tare beam upon the laterally projecting arms M^2 and M^3 , would tend to throw the beam out of balance. This I have overcome by connecting the steelyard rod on an oppositely off-set portion of the beam M shown at M^5 Fig. 4. Thus the pull of the steelyard rod is upon one side of the plane of the fulcrum for the beam M , and the tare beam is upon the opposite side of said plane, thereby effecting a counterbalance.

What I claim as my invention is:

1. In a scale the combination with a beam, of a recessed counterpoise attached thereto, a guide for said counterpoise in axial alinement therewith and engaging the recess therein, and a shelf on said guide forming a support for detachable weights for said counterpoise.

2. In a scale the combination with a fulcrumed beam, of a tare beam mounted thereon and off-set from the plane of the fulcrum, and a steelyard rod for operating said beam engaging a portion thereof oppositely off-set from the plane of said fulcrum.

3. In a scale the combination with a platform and index and connecting mechanism therebetween, of a beam or lever forming an element of said connecting mechanism, a tare beam off-set in front of the plane of said beam and mounted on the latter, and a steelyard rod for operating said beam engaging a portion of the latter and oppositely off-set from the tare beam.

4. In a scale, the combination with a frame, of a beam, a recessed counterpoise attached thereto, a shelf on said frame, a guide carried by said shelf engaging the recessed portion of the counterpoise, and a slotted detachable weight adapted to be supported on said shelf with the slotted portion thereof engaging the guide.

5. In a scale, the combination with a base having an extension, platform levers within the base, a platform supported on said levers, an upwardly extending frame above said extension of the base, an indicating section on said frame, an index hand and a tare beam both fulcrumed on said upwardly extending frame, a pendulum weight for said index hand, a steelyard rod connection between said platform levers and beam, and a connection between the latter and the index hand.

6. In a scale, the combination with a base having an extension, platform levers within the base, a platform supported on said levers, an upwardly extending frame above said extension of the base, an indicating section on said frame, an index hand fulcrumed on said upwardly extending frame, a tare beam fulcrumed on said upwardly extending portion of the frame beneath said index hand, a pendulum weight for said index hand, a steelyard rod connection between said platform levers and beam, and a connection between the latter and the index hand.

7. In a scale, the combination of a base, platform supporting levers therein, a standard on said base, an indicating section carried by said standard, an index, a pendulum weight, a lever fulcrumed within the standard, a tare beam arranged in front of the standard and mounted upon said lever, and an operative connection between said lever, the platform levers and said index.

8. In a scale, the combination of a base, a hollow standard rising therefrom, an indicating section mounted on the hollow standard, platform levers arranged in the base, a platform supported on the levers, a lever within said hollow standard, a tare

beam without the standard attached to said lever, an index hand, a pendulum weight connected thereto, a connection operatively attaching the lever to the index hand, and an operative connection between the lever and the platform levers.

9. In a scale, the combination of a base, a hollow standard rising therefrom, an indicating section mounted on the hollow standard, platform levers arranged in the base, a platform mounted on said levers, a lever fulcrumed within said hollow standard and having a portion extending therewithout, a tare beam, a connection between the latter and the extension of the lever, a connection between the lever and the tare beam extending through the hollow standard, an index hand, a pendulum weight attached thereto, and an operative connection between the lever, the platform levers and the index hand.

10. In a scale, the combination with a base, a standard rising therefrom, an indicating section on said standard, platform levers in the base, an index hand fulcrumed on said standard, a pendulum weight for the index hand, a lever fulcrumed on the standard having a portion off-set to one side of its fulcrum, a tare beam arranged upon the opposite side of the fulcrum of said lever and attached to the latter, and an operative connection between said index hand, said lever and said platform levers, including an operative connection for said lever attached to the off-set portion thereof. 35

In testimony whereof I affix my signature in presence of two witnesses.
